[57] CLAIM

The ornamental design for a sole for rocking exerciser
or the like, as shown and described.

DESCRIPTION

FIG. 1 is a top plan view of a sole for rocking exerciser
or the like showing our new design;
FIG. 2 is a bottom plan view thereof;
FIG. 3 is a front elevational view thereof;
FIG. 4 is a rear elevational view thereof;
FIG. 5 is a left side elevational view thereof; and,
FIG. 6 is a right side elevational view thereof.
